Inventor

Leon Cammen

By Attorney

UNITED STATES PATENT OFFICE.

LEON CAMMEN, OF NEW YORK, N. Y.

CENTRIFUGAL CASTING MACHINE.

Application filed April 14, 1926. Serial No. 102,047.

The present invention refers to molds for centrifugal casting machines, and more specifically machines which cast not tubes, but a number of separate castings, such as ingots, bars, slabs and the like. In such machines the problem of removing the cast bars from the machine is an important one. The present invention sets forth means for doing this expeditiously.

10 In the illustrations,

Fig. 1 is a section of the mold in a plane normal to the axis of rotation;

Fig. 2 is a view, looking from on top, of the element indicated in Fig. 1 as 4;

15 Fig. 3 is a section through one of the rollers 4 in Fig. 2.

If the mold consisted merely of the barrel 1 and dividing bars 2, the castings 3 would lie in the position shown in Fig. 1 as long 20 as the mold is spinning, the centrifugal force holding them against the wall of the barrel. As soon however as the speed of spinning decreased below a certain level, the bars which happened at that time to be in the top part 25 of the mold, not held any more by centrifugal force, would come down and pile up in a heap. This, besides marring the surface of the mold, would also make it very difficult to remove the cast bars from the mold 30 by any kind of a mechanical device, as the cast bars would be piled up indiscriminately, and a mechanically operated grabbing device would have difficulty in getting a full hold on a bar. Because of this, it becomes 35 necessary to provide some means by which the bar would clear away from the mold in the upper part of the latter, to enable the jaws of a grabbing device to get a good hold on the bar, and yet the cast bar would not 40 fall all the way down, but would stay at a predetermined distance from the mold.

The present inventor solved this problem in his U. S. Patent No. 1,553,136 by providing the dividing bars 2 with shoulders. The 45 present invention is a modification and further improvement of the device there shown. If the shoulders of the bars shown in the patent above were extended until they met, a construction would be obtained substantially 50 like the one shown in Fig. 1. Fig. 1 permits however to introduce the improvement shown in Fig. 2. In this the piece 4 is replaced by a roller bed of the type familiar to rolling mill designers, and consisting of 55 frame bars 6 and 7 which are shown here

as attached to the dividing bars 2 by means of pins or bolts 52, and rollers 4 with their pins 8. The purpose of this is to reduce the amount of power necessary to pull the bars out of the mold, and to permit to pull them 60 faster.

The pieces 4 are merely intended to provide supports for the cast bars 3, and to prevent them from falling out of the mold when the latter stops spinning. It is therefore 65 entirely immaterial (except from other considerations, such as questions of heat dissipation) whether the pieces 4 are made of solid plate from end to end, or perforated, or made up of strips placed at some intervals. It is likewise immaterial whether the pieces 4 are individual, or form part of a cage running all around the mold.

Furthermore, while in Fig. 1 the pieces 4 are shown attached to the dividing bars 2 75 by pins or bolts 52, it should be clearly understood that this is merely a preferred construction, recommended because it is simple and can be made very rugged. Other constructions may however be adopted with the 80 present invention, where the added cost and complications are not considered objectionable. Thus the cage consisting of the pieces 4 may be held on some kind of a spider, possibly attached to mold barrel 1, and spinning with it, but outside of the barrel proper, and may be slid into it at the proper time, e. g. when the bars are ready for pulling. This is however obviously merely a 85 modification of the construction shown in 90 Fig. 1, and actually becomes the construction shown in Fig. 1 at the time when this construction is useful. The means to slide the cage into and out of the barrel of the mold are not shown, as they are very simple and of such a character that any engineer 95 who has realized the purpose of said means, will have no difficulty to design them to suit his particular conditions.

I claim:

1. A mold for centrifugal casting having partition lugs, and means external to the lugs and positioned within the mold to retain in spaced relation to the wall of the mold castings not held thereto by gravity. 100
2. A mold for centrifugal casting having partition lugs, means external to the lugs and positioned within the mold to retain in spaced relation to the wall of the mold castings not held thereto by gravity, and 105
3. A mold for centrifugal casting having partition lugs, means external to the lugs and positioned within the mold to retain in spaced relation to the wall of the mold castings not held thereto by gravity, and 110

antifriction means upon said castings support means to facilitate withdrawal of the castings.

3. A mold for centrifugal casting having partition lugs, and means external to the lugs to retain in spaced relation to the wall of the mold castings not held thereto by

gravity, said casting support means being axially insertable and removable with respect to the mold.

Signed at New York, in the county and State of New York, April 13, 1926.

LEON CAMMEN.
